Specification for Design.

Patented Feb. 10, 1920.

Application filed March 26, 1919. Serial No. 285,389. Term of patent 7 years.

To all whom it may concern:

Be it known that I, CHARLES POHL, a citizen of the United States, residing at Los Angeles, in the county of Los Angeles and State of California, have invented a new, original, and ornamental Design for an Auto-Lock, of which the following is a specification, reference being had to the accompanying drawings, forming part thereof.

Figure 1 is a face view of one side of the lock.

Fig. 2 is a face view of the other side of the lock from that shown in Fig. 1.

Fig. 3 is an edge view.

I claim:

The ornamental design for an auto lock, as shown.

Signed at Los Angeles, California, this 25th day of January, 1919.

CHARLES POHL.
